UNITED STATES PATENT OFFICE

146,395

DESIGN FOR WALLPAPER BORDER OR SIMILAR ARTICLE

Ada Westrate, Chicago, Ill., assignor to The Meyercord Co., Chicago, Ill., a corporation of Illinois

Application April 4, 1946, Serial No. 128,260

Term of patent 3½ years

(CL D59—10)

To all whom it may concern:

Be it known that I, Ada Westrate, a citizen of the United States, residing at Chicago, in the county of Cook, State of Illinois, have invented a new, original, and ornamental Design for Wallpaper Border or Similar Article, of which the following is a specification, reference being had to the accompanying drawing, forming a part thereof, wherein the figure is a plan view of wallpaper border showing my new design.

I claim:

The ornamental design for wallpaper border or similar article, as shown.

ADA WESTRATE.
